GLOSSY COATING MACHINE AND METHOD
 Raymond A. Labombarde, Lowell Road, Nashua, N.H.
 Continuation of application Ser. No. 69,055, Nov. 14,
 1960. This application May 13, 1964, Ser. No. 369,654
 36 Claims. (Cl. 117—64)

This application is a continuation of my application Serial No. 69,055, filed November 14, 1960, now abandoned, and entitled Glossy Coating Machine and Method.

This invention relates to a machine and method for producing a glossy coating on waxed paper box blanks.

This term waxed paper box blanks is intended to mean blanks which are coated with hot melt coating compositions containing paraffin wax, microcrystalline wax, polyethylene or similar ingredients and which are used to make folding cartons for frozen foods. Ordinary wax coatings lack lustre and it is desirable to impart a gloss to the same to increase the visual impact and customer appeal of the frozen food cartons.

It has been proposed in U.S. Patent No. 2,892,735 to Curlier of June 30, 1959, to press the wax coated blanks on a smooth, hard surfaced, endless belt, having a stretch about fifteen feet long, to smooth the coating into a high gloss finish and then to strip the blanks from the belt. In the copending application of Philip D. Labombarde, Serial No. 862,192, filed December 28, 1959, Patent No. 3,070,457, Dec. 25, 1962, the subject matter which is in application Serial No. 280,760, filed May 15, 1963, for reissue and entitled Apparatus and Method for Glossy Wax Coating the blanks are first coated with a thin layer of hot melt coating composition. Then the top of the layer is removed and replaced by hot, reverse coating rolls, reliquified by hot flames and then quenched by a cooling waterfall all for producing a high gloss finish.

Both of these systems require a relatively lengthy machine, and floor space is usually at a premium in box making or foodstuff packing plants. In addition, both of these systems operate on the principle of applying the hot melt coating to the blank and then seeking to smooth the coating to a high gloss while on the blank.

The object of this invention is to provide a low coat, relatively short machine for producing a glossy finish, the finish being glossy when it leaves the coating zone as a result of the coating operation.

Another object of the invention is to provide a machine and method whereby both the upper and lower faces of individual and successive flat box blanks may be coated in one pass through a short roll coating zone, at least one face being glossed before it leaves the coating zone.

A further object of the invention is to provide reverse roll coating means for applying a smooth, glossy coating to one face of a plurality of flat, individual, successive box blanks each of which has been coated in the same zone on its opposite face with a hot melt coating composition and is, therefore, slippery and difficult to handle.

Still another object of the invention is to provide a roll coating machine for coating box blanks on both faces with a hot melt coating composition, wherein the roll of the final pair of rolls may be either a cold steel roll for hardening a coating, a hot burnishing roll for polishing the coating or a hot reverse coating roll for applying a final smoothing layer.

An important object of the invention is to provide novel roll coating apparatus for handling individual and successive sheets which may be uncoated and dry, coated, dry and slippery or coated, wet and slippery on either or both faces. The apparatus successfully grips and advances such sheets through the nip of opposed coating rolls, one of which is reversely rotating

and applying a hot melt coating to the adjacent face of the sheets, because the other roll is rotating and chilled to secure frictional contact sufficient to overcome the reversing effect of the opposite roll.

5 A still further object of the invention is to provide a roll type machine for reverse roll coating a smooth glossy layer on the adjacent faces of individual blanks advancing along the paper line of the machine, the machine including a thin flexible wiper blade in tangential contact with the coating on the roll for smoothing and glossing the coating just before it is deposited on the blanks.

10 Other objects and advantages of the invention will be apparent from the claims, the description of the drawings and from the drawings in which

15 FIG. 1 is a side view of the preferred form of the invention.

FIG. 2 is a plan view of the machine shown in FIG. 1.

15 FIG. 3 is an end view, in section on line 3—3 of FIG. 2.

20 FIG. 4 is an enlarged, detail, side view of the tangential, flexible, smoothing blade of the invention.

FIG. 5 is a side view in section on line 5—5 of FIG. 2 showing the drive means for the rolls.

25 FIG. 6 is a diagrammatic, perspective view of the coating rolls illustrating the means for continuously gripping and advancing the blanks even though wet, slippery and being reverse roll coated.

FIGS. 7, 8, 9, 10, 11, 13 and 14 are diagrammatic 30 side views illustrating the various capabilities of the machine of this invention for producing finishes ranging from commercially acceptable to commercially superior.

FIG. 12 is a view similar to FIG. 5 showing the drive means for the rolls when the coating treatment of FIG. 35 11 is desired.

35 In the drawings the coating apparatus 20 is shown occupying a relatively short coating zone 21, which may be four to six feet in length. The machine 22 also includes a feeding zone 23 for a blank feeding apparatus 24 of any well known type and a cooling zone 25 for cooling apparatus 26 of any well known type. The blank feeding apparatus 24 is preferably the "Speed King" manufactured by the International Paper Box Machine Company of Nashua, New Hampshire, this apparatus permitting three lane operation, although any equivalent feed can be used in this invention which will advance flat blanks individually and successively along the paper line P into the coating zone 21. The cooling apparatus 26 may be of the "HW" type manufactured by 40 the said International Paper Box Machine Company or any equivalent device for carrying coated blanks through a cooling zone while immersing or showering the same with a coolant fluid such as water.

45 The coating apparatus 20 includes the frame 27 upon which three pairs 28, 29 and 30, of opposed, upper and lower rolls are journaled, each having a nip such as 32, 33 and 34 along the paper line P. The first pair of rolls 28 is for the purpose of applying a thin layer of hot melt coating composition to one face 35 of the flat box blanks such as 36 and 37 fed into the nip 32 by the feeding apparatus 24. Suitable blank carrier rolls 38 are provided to bridge the gap between the nip 32 and the feed apparatus 24. The face 35, which is the lower face of the blanks, will be the inside face of the carton folded from each blank and it is, therefore, unnecessary that it have a glossy wax finish. It should also be noted that the upper face 39 of each blank is dry and uncoated, and that the blank is usually at room temperature when it enters the nip 32 so that slippage has not yet become a factor. The upper roll 41 of the first pair of rolls 28 may thus have a hard steel face 40 or a yieldable rubber face and still secure a good friction grip on the blanks to advance

the blanks through the nip 32 toward the nip 33. The lower roll 42 of the pair of rolls 28 is a coating roll and it is preferred that it have a yieldable rubber cylindrical face 43 formed by a rubber sleeve 44 on a metal roll body 45. The roll body 45 is hollow and heated to a temperature substantially the same as the melting point of the coating composition. The yieldable rubber face 43 is supplied with the coating composition by a suitable feed roll 46 rotating in a coating tank 47, the roll 46 also serving as a doctor roll for metering the thickness of the coating. The coating composition 48 in tank 47 is maintained at a temperature above the melting point by continual circulation from a heated reservoir in a manner to be described. Preferably the roll 42 is a reverse coating roll, as shown, although a forwardly, rotating coating roll is satisfactory for coating the unglossed, lower face of the blanks.

It will be self evident, that while a continuous web could be drawn through a pair of opposed, reversely rotating coating rolls to simultaneously reverse coat an upper and a lower layer thereon, this is not possible with a succession of individual blanks. The nip of the rolls would move the blanks rearwardly rather than forwardly if it moved the blanks at all. It is also apparent that reverse roll coating the upper faces of a succession of individual blanks while the lower faces are wet and slippery with a hot melt coating presents the problem of securing a frictional grip for advancing the blanks through the roll nip.

In order to be able to reverse coat an upper layer 49 of hot melt coating composition on the blanks 36 and 37, in the shortest space possible after the application of the lower layer 50 applied by lower roll 42, means must be provided for frictionally gripping the blank by its still hot and slippery layer 50. This is accomplished by the second pair of rolls 29 which include the chilled, hard faced, lower roll 51 and the heated, yieldable faced, upper roll 52 which form the nip 33. The upper roll 52 is provided with a rubber sleeve 53 having a yieldable rubber cylindrical face 54 which deposits the coating in any recesses, creases, etc., in the blanks and also along the edges of the blanks 36 and 37 in the same manner as does the rubber faced coating roll 42. A hard faced, steel doctor roll 55 is provided to form a nip reservoir 56 of hot melt coating composition with roll 52, the roll 55 being adjustable to meter the thickness of the coating 56 on the face 54. The roll 52 is reversely rotated by the coating roll drive means of the invention and the speed of the blanks also permits the thickness of coating to be controlled. It has been found that the coating applied by the reverse coating roll 52 tends to pile up at the nip 33, as shown diagrammatically herein, and tends to be smoothly applied to the material being coated without nip marks, and with a glossy finish. The body 57 of roll 52 is hollow and heated to a temperature above the melting point of the hot melt coating composition 48 as is the doctor roll 55. A conduit 59 feeds the composition 48 to the nip reservoir 56 as part of the coating composition supply means 58 of the machine 22.

The lower roll 51 is called a blank advancing and chilling roll since it is of steel and provided with a hard, smooth cylindrical face 60. Roll 51 is hollow and connected by conduits such as 61 to a refrigerant reservoir 62 there being suitable chilling mechanism 63 of any well known type and a suitable pump 64 and motor 65 for maintaining circulation. Preferably the face 60 is maintained at a temperature well below the melting point of the composition 48, for example, if the melting point of the composition is 135° F. to 250° F. the cylindrical face 60 is at 60-70° F. The roll 51 is forwardly rotated so as to advance the blanks 36 and 37, at the nip 33, along the paper line P and because the roll is chilled, it is able to frictionally grip the slippery lower layer 50 and also to harden the layer. A suitable scraper blade 66 is provided to scrape any hard wax accumulations from the

face 60 of roll 51, the pressure of the blade 66 being adjustable by a hand wheel 67.

The engagement of the chilled face 60 with the lower layer 50 of each individual and successive blank at nip 33 not only chills and hardens the layer but tends to chill the body of the blanks thereby preventing the thin upper layer 49 from impregnating into the body of the blank and causing the lower portion of the upper layer to harden on the upper face 39 of the blanks. The blanks are frictionally advanced by the chilled face 60 from nip 33 to nip 34 of the third pair of rolls 39 even though the coating roll 52 is reversely rotating relative to the direction of advance of the blanks.

The pair of rolls 30 includes the lower roll 70 of metal such as steel, the roll 70 having a hard smooth cylindrical face 71 and being hollow for the passage of the refrigerant fluid. Roll 70 is thus an advancing and chilling roll, rotated forwardly, in the same manner as roll 51 and connected by conduit 72 to the refrigerant circulation system 63 of the machine. A frictional grip on the lower layer of coating on each blank is thus assured to advance each blank through nip 34 and into the cooling zone 25 or into a tempering zone to be hereinafter described and located in advance of the cooling zone. A scraper blade 73, similar to blade 66 is provided for removing accumulations from the face 71, the blade 73 being also adjustable by the hand wheel 67 through a common rod and spring mechanism 74.

The upper roll 75 of the pair of rolls 30 is called a glossing roll herein and the machine 22 is so constructed that glossing roll 75 may be a second heated reverse coating roll, a heated reversely rotating burnishing roll or a chilled forwardly rotated advancing and chilling roll.

As shown, roll 75 is preferably a second, heated, reverse coating roll identical with reverse coating roll 52 and includes a rubber sleeve 76, a yieldable rubber cylindrical face 77, a hollow metal body 78, and conduits 79 and 80 connecting the interior of body 78 to the roll heating system 81 of the invention. The roll 75 is reversely rotated by the coating roll drive means 82 of the machine 22, and a doctor roll 83, similar to doctor roll 55, and heated by connection to the roll heating system 81 forms a nip reservoir 84 similar to nip reservoir 56 for metering the thickness of the coating 85 on the face 77 of roll 75. A conduit 86 feeds a supply of the hot melt wax composition to the reservoir 84 from the supply means 58. The speed of the reverse coating roll 75, or the clearance of the doctor roll 83 may be adjusted for the deposit of a layer 90 of coating composition, equal in thickness to the layer 49, on the layer 49, both layers being extremely thin and the overlying layer tending to fill in any nip marks, crows feet, pock marks or the like in the underlying layer.

Each of the upper rolls 41, 52 and 75 are mounted in bearings such as 87, 88 and 89, spring pressed downwardly by coil springs such as 91. To convert roll 75 to a reversely rotating burnishing roll it is only necessary to slidably remove the rubber sleeve 76 and shut off the supply of hot melt coating composition to nip reservoir 84 by shut-off valve 92. The upper layer 49 on the blanks 36 and 37 is thus polished to a high gloss as it passes through the nip 34. The cylindrical face 93 of the roll body 78 is hard and smooth for producing a high gloss on the layer 49 when the springs 91 press the roll downwardly into engagement with the coating. To convert the roll body 78 into an advancing and chilling roll, similar to rolls 51 and 70 the conduits 79 and 80 are disconnected from attachment to roll body 78 and the conduits 94 and 95 are substituted therefor, thus connecting the roll body 78 to the refrigerant system 63. Inasmuch as the chilled roll face 93 would frictionally grip and retard the blanks, if reversely rotating, the drive connection 96 to the reverse roll rotating means 82 is reversed to cause the roll body 78 to forwardly rotate.

In FIG. 5, the normal and standard drive means 82,

for accomplishing the various possible treatments illustrated diagrammatically in FIGURES 7, 8, 9 and 10, is illustrated. The electric motor 99 drives a speed regulator 100, and one shaft 101, of regulator 100, is connected by a power train 102 to drive the intermeshed gears 103 and 104, gear 103 being carried by the shaft 105 of the upper coating roll 52 and reversely rotating the roll 52. The gear 104 rotates the doctor roll 55 in the direction of the arrow. In the preferred embodiment, the shaft 105 is connected by the sprocket and chain power train 106, to also rotate the upper roll 75 reversely on its shaft 107. The intermeshing gears 103 and 109, cause shaft 107 to rotate the shaft 110 of doctor roll 83 in the direction of the arrow.

The other shaft 114, of regulator 100 through power train 115, rotates the shaft 116 of the lower roll 70 in the direction of the arrow. A power train 117 connects the shafts 119, 118 and 116 of the lower rolls 42, 51 and 70 to cause all of these rolls to rotate forwardly in the direction of the arrows. Intermeshing gears 120 on shaft 119, and 121 on shaft 122 of upper roll 41, cause these rolls to rotate as shown and intermeshing gears 123 on shaft 122 and 124 on shaft 125 cause a doctor roll 126 on shaft 125 to rotate in the direction shown, if such a roll is desired, as in FIG. 7. The gear 120 on shaft 119 also drives a gear 127 on shaft 128 of doctor roll 46 to rotate the roll in the direction shown.

The roll heating system 81 includes the jacket 131 containing hot oil 132 and encircling the reservoir 133 which contains the hot melt coating composition 48 of the supply means 58. Suitable heating elements 134 maintain the oil 132 at well above the melting point of composition 48 and also maintain the composition 48 in reservoir 133 at a temperature above the melting point thereof, for example, 350° to 400° F. The hot oil 132 is continuously circulated through the coating rolls 42, 52 and 75, the doctor rolls 46, 55 and 83 and the jacket 131 by hot oil conduits such as 79, 80 and 135, 138 and a hot oil pump 136. The composition 48 is continuously fed to the coating tank 47 and to the nip reservoirs 56 and 84 by the conduits such as 59 and 86 from the reservoir 133 of the supply means 58 through pump 137. The chilling mechanism 63 for the lower rolls 51 and 70 may be of any well known commercially available type capable of circulating a refrigerant from the reservoir 62 through conduits such as 61. The refrigerant conduits 94 and 95 form part of the system for chilling roll 75 when the hot oil conduits 79 and 80 are disconnected therefrom.

The upper, heated, reverse coating roll 52, and the glossing roll 75, when serving as a secondary upper heated reverse coating roll, are preferably each equipped with a thin, flexible, wiping blade such as 140 or 141. The wiping blades 140 or 141 are about three one-thousandths inch in thickness and formed of flexible, resilient material such as sheet metal. Each blade such as 140 includes longitudinally spaced slots 143 in which the pins 144 of a clamp bracket 145 are enclosed as best shown in FIG. 4. The jaw 146 of bracket 145 is fixed to the bracket body 147 by the machine screws 148 and both the bracket and the blade are coextensive in length with the rolls 52 or 75. Bracket body 147 is journalled at each opposite end in the frame of machine 22 and carries a clamp link 150 pivotally connected to a push rod 151 slidable in a fixed bracket 152. The rod 151 is normally spring loaded upwardly by coil spring 153 to maintain the bracket 147 in the desired position but downward pressure on the knob 154 of rod 151 will cause the bracket to turn on its longitudinal axis and then spring back to its normal position.

As shown in dotted lines in FIG. 4 the blade 140 would be in extension of the clearance slot 155, if there were no coating roll, but, as shown in full lines, the roll flexes the blade into the curve shown. The free terminal edge 156 of the blade extends along the line of tangency with the

roll, but the blade is deformed away from a tangential plane as shown. The pressure and the flex of the blades 140 and 141 is adjusted by moving the collar 157 on the push rod 151. It has been found that the wiping blades can be adjusted, while the operator examines the coating carried from the nip reservoir around to the roll nip, until that coating has been smoothed and leveled to an unbroken, high gloss, mirror-like finish on the roll. The blanks are then passed through the machine and the coating which has been so glossed on the roll is transferred to the blanks by reverse coating with the high gloss finish retained. A small accumulation of the coating composition occurs in advance of the edge 156 but the thinness of the metal and the heat of the composition and the coating roll prevents the same from hardening. The blade is caused to remain hot by forming the bracket 145 of a low heat conductive material such as Formica. If specks or particles become trapped in advance of the edge 156, the operator pushes down on knob 154 which flexes the blade toward the roll and causes the edge 156 to move slightly away from the face 77 to release the speck or particle. Any longitudinally extending depressions caused in the upper layer coated on the blanks, by such a speck or particle is covered and eliminated by the second layer reverse coated thereon by the roll 75.

In FIG. 7 the machine and method of the invention is illustrated diagrammatically as producing a commercially acceptable glossy finish. In FIG. 7 there are no wiper blades such as 140 and 141 and the upper roll 75 of the third pair of rolls is a chilling and advancing roll. The upper layer 49 reverse coated by the upper roll 52 on the blanks 36 is glossed by the quick chilling action of the roll body 78 of upper roll 75 and retains the gloss after cooling in the cooling zone 25.

As shown, the upper roll 41 and the lower roll 42 can both apply a coating simultaneously if desired because both are rotating forwardly to advance the blanks through the nip. A rubber sleeve 164, identical with sleeve 44, is mounted on roll 41 and it is supplied with coating composition, by means of the doctor roll 126. In the embodiments of FIGURES 8, 9, 10 and 11, however, the upper roll 41 is merely a dry, blank-advancing roll without the sleeve 164.

In FIG. 8 a wiper blade 140 has been provided for the reverse coating roll 52, thereby smoothing and leveling the coating to a greater degree and producing a finish with more gloss and the equivalent of products now on the market.

In FIG. 9 the preferred form of the invention is shown in which the upper rolls 52 and 75 are both reverse coating rolls and each is equipped with a wiper blade 140 or 141. The finish achieved by this apparatus and method is highly glossy since both the primary and the secondary layers have been leveled on the rolls prior to deposit on the blanks. The high gloss finish achieved by this apparatus is mirror-like and of a superior character.

In FIG. 10 the roll 75 is a reversely rotating burnishing roll, in order to show that this capability of machine 22 is possible although not preferred. In this modification the coated blanks are passed through a commercially available hot air oven 160 for slightly softening but not liquefying the exposed area of the upper layer or layers. This zone is called a tempering zone because it also includes a waterfall type quenching device 161 for quickly cooling the finish softened in the oven. It has been found that while a hot melt coating composition may be given a gloss, or a high gloss, by the apparatus of this invention, or by the devices of the prior art heretofore mentioned, the finish may still remain tacky and soft. By tempering the finish as described above the finish is hardened and set without adversely affecting the gloss.

The coating composition 48 may be paraffin wax, microcrystalline wax, polyethylene or various desired combinations of the same, or may be other suitable coating compositions. It will be noted that in the diagrammatic views of FIGURES 7, 8, 9 and 10 the three lower

rolls 42, 51 and 70 all rotate forwardly rather than reversely, the upper roll 41 rotates forwardly and the upper roll 52 rotates reversely. The upper roll 75 rotates reversely in the preferred embodiment of FIG. 9, as well as in the embodiment of FIG. 10. For rotating roll 75 forwardly, as in FIGS. 7 and 8, the power train 106 is disconnected from shaft 105 and connected to a sprocket 123 on shaft 122.

The treatment capability shown in FIG. 11 is similar to that shown in FIGURE 8 except that the coating on the underface of the blanks is applied by reverse coating. As shown in FIG. 12 the power train 106 connects shafts 122 and 107 to rotate rolls 41 and 75 forwardly. The shaft 119 is disconnected from the power train 117 and is reversely rotated by means of intermeshing gears 120 and 179, the latter being rotated by a power train 171 to the drive shaft 101 of regulator 100.

It should be noted that in the embodiment of FIG. 1, and in FIG. 11, upper roll 41, while opposing a reversely rotating coating roll 42, need not be chilled because the sheets arriving at the nip of the rolls are dry, uncoated and not slippery. However, if for some reason it was desirable to deliver the sheets to this particular nip with the upper face wet and coated, the roll 41 would be chilled to become an advancing and chilling roll such as rolls 51 and 70.

In FIG. 13 the most simplified form of the coating apparatus 20 is illustrated to represent what is believed to be the basic invention herein. The three pairs of rolls 28, 29 and 30 in the coating zone 21 of machine 22 are illustrated, but the third pair 30 serve merely as conventional blank carrier rolls similar to carrier rolls 38. The blanks 36 are coated on the underface 35 by the coating roll 42 whereby they arrive individually and successively at the nip 33 of rolls 51 and 52 with one face 35 wet and slippery with coating. A layer 49 is applied to the uncoated faces of the blanks, at nip 33, by the reversely rotating, heated, roll which is supplied with coating from the reservoir 56 as described above, the reverse coating action providing a smooth glossy surface. The other roll 51 of the pair of rolls 29 rotates forwardly relative to the path of the blanks and secures a frictional grip on the wet slippery underfaces of the blanks by reason of being chilled. Unlike a knurled roll, the smooth chilled face of roll 51 does not damage or mark the coating and also tends to harden the coating on the blanks.

In FIG. 14, the same basic structure is illustrated as in FIG. 13 with the addition of at least one pair 170 of opposed rolls 171 and 172 which are pre-heating rolls as well as carrier rolls. The rolls 171 and 172 may be connected by suitable conduits, to the hot oil heating system 81 of the machine 22 and will thus be maintained at about the same temperature as the heated coating rolls of the apparatus. Pre-heating by the nip of a pair of heated rolls has been found to improve the smoothness and gloss of the coating applied in coating zone 21 and serves to iron out and flatten the fibrous faces of the blanks just before they are coated.

I claim:

1. Apparatus for coating a plurality of box blanks in one pass through a short coating zone of a coating machine, said apparatus comprising means for feeding said blanks individually and successively into said coating zone; a first pair of opposed rolls in said zone, said rolls having a nip for receiving and advancing said blanks along said zone; means on said machine for applying a hot, wet, slippery coating to at least one roll of said first pair for coating at least one face of said advancing blanks, thereby causing said blanks to advance beyond said nip with a hot, wet, slippery coating on one face thereof; a second pair of opposed rolls in said zone, said rolls having a nip closely spaced in rear of, and receiving each said blank from, the nip of said first pair of rolls while the said coated face thereof is still hot, wet and slippery; means for reversely rotating one roll of said second pair and for-

wardly rotating the other roll of said second pair; refrigerant supply means for chilling the forwardly rotating roll of said second pair to a temperature causing hardening of each hot, wet, slippery coating engaged thereby to grip and further advance said blanks through said nip and further along said zone, and means for applying a coating to the reversely rotating roll of said second pair for completing the coating on the other face of said advancing blanks.

10 2. Apparatus as specified in claim 1 wherein the forwardly rotating, chilled roll of said second pair of rolls includes a smooth, hard cylindrical face of metal.

15 3. Apparatus as specified in claim 1 wherein each roll of said first pair of rolls to which said coating is applied includes a blank engaging face of yielding rubber-like material.

20 4. Roll coating apparatus for reverse roll coating one face of a plurality of flat blanks advancing individually and successively along a path with the other face of said blanks wet and slippery with hot melt coating, and for hardening said coating, said apparatus comprising a pair of opposed rolls having a nip in said path for receiving said blanks while said coating is still hot, wet and slippery, and advancing said blanks; means for continuously supplying a hot melt coating composition to the face of the roll of said pair in engagement with the uncoated faces of said blanks; means for reversely rotating the said roll in relation to the path of said blanks for reverse roll coating the uncoated faces thereof; means for forwardly rotating the other said roll in relation to the path of said blanks, a hard, smooth cylindrical face on said forwardly rotated roll, and refrigerant means for chilling the face of said forwardly rotated roll to cause the hot, wet, slippery coating engaged thereby to harden while frictionally gripping and advancing said blanks through said nip against the reversing effect of the said reversely rotating roll of said pair.

30 5. Apparatus for producing a glossy coating on paper box blanks, said apparatus comprising a first pair of opposed, nip-forming rolls including a lower blank coating roll and an upper blank advancing roll; a second pair of opposed, nip-forming rolls including an upper blank coating roll and a lower blank advancing and chilling roll; a third pair of opposed nip-forming rolls including an upper blank glossing roll and a lower blank advancing and chilling roll; drive means for reversely rotating said upper blank coating roll; drive means for forwardly rotating said blank advancing rolls and drive means for rotating said glossing roll; means for supplying hot melt coating composition to the faces of said coating rolls and means for chilling the faces of said blank advancing and chilling rolls, whereby said blanks are advanced individually and successively through the nips of said rolls by said chilled rolls and the upper coating thereon is glossed by said glossing roll.

45 6. Apparatus as specified in claim 5 wherein each said blank advancing and chilling roll includes a hard, smooth, cylindrical face and each said coating roll includes a yieldable, rubber, cylindrical face.

7. Apparatus as specified in claim 5 wherein said coating rolls each include a yieldable, rubber, cylindrical face for depositing said coating in any depressions in said box blanks.

65 8. Apparatus as specified in claim 5 wherein said means for chilling the faces of said blank advancing and chilling rolls includes means for chilling the faces of said rolls to well below the melting point of said hot melt coating composition.

70 9. Apparatus as specified in claim 5 plus a steel doctor roll rotatably engaging each said coating roll for metering the thickness of the coating thereon and means for heating each said doctor roll.

10. Apparatus as specified in claim 5 plus a thin, flexible smoothing blade of sheet material about three thousandths inch in thickness associated with each said coat-

ing roll, the free terminal edge portion of said blade being in tangential wiping engagement with a coating on said roll just in advance of the roll nip.

11. Apparatus as specified in claim 5 plus a blade holder of low heat conductive material mounted parallel to each said coating roll, a thin flexible, sheet metal blade supported in said holder and having its free terminal edge portion in tangential wiping engagement with a coating on said roll and means for rotating said holder on its longitudinal axis for flexing said blade into and out of said tangential engagement.

12. Apparatus as specified in claim 5 wherein said upper, blank, glossing roll is a chilled, steel roll having a hard, smooth cylindrical face and said glossing roll drive means is adapted to forwardly rotate said roll.

13. Apparatus as specified in claim 5 wherein said upper blank glossing roll is a heated burnishing roll having a hard, smooth cylindrical face and said glossing roll drive means is adapted to reversely rotate said roll.

14. Apparatus as specified in claim 5 wherein said upper blank glossing roll is a heated coating roll and said glossing roll drive means is adapted to reversely rotate said roll.

15. A machine for producing a glossy coating on paper box blanks, said machine comprising means for feeding blanks individually and successively along a path into a coating zone; coating apparatus in said coating zone, said apparatus comprising a plurality of pairs of opposed upper and lower rolls, each having a nip for advancing said blanks through said coating zone, means for supplying hot melt coating composition to a lower coating roll of one said pair and to the upper coating roll of another said pair, means for reversely rotating said coating rolls and forwardly rotating the remainder of said rolls; means for chilling the face of the upper and lower roll succeeding each said upper and lower coating roll for hardening the layer and frictionally gripping said coated blanks deposited thereby; a thin, flexible, metal blade mounted on said machine, the terminal edge thereof being in tangential engagement with said upper coating roll just in advance of the nip thereof for leveling said coating before reverse coating thereof on a blank and a rotatable blade-supporting bracket of low heat conductive material for resisting transfer of heat from said blade and adjusting the flex of said blade relative to said coating roll.

16. A method for continuously producing a high gloss, smooth coating on fiat box blanks, said method comprising the steps of advancing said blanks individually and successively along a path by forwardly rotating roll contact with the upper face thereof while roll coating a thin layer of hot melt coating composition on the lower face thereof; then advancing said blanks individually and successively further along said path by chilled forwardly rotating roll contact with the coated lower face thereof while simultaneously reverse roll coating a thin layer of hot melt coating composition on the upper face thereof, and then advancing said blanks individually and successively further along said path by chilled forwardly rotating roll contact with the coated lower face thereof while roll glossing the coating on the upper face thereof.

17. A method as specified in claim 16 plus the step of smoothing and leveling said thin layer of hot melt coating composition just before said layer is reverse roll coated on the upper face of each said blank.

18. A method as specified in claim 16 wherein said reverse roll coating steps each include the step of resiliently and yieldably applying said coating.

19. A method as specified in claim 16 wherein said chilled direct roll contact steps each include the step of chilling said coatings to well below the melting point of said hot melt composition.

20. A method as specified in claim 16 wherein said roll glossing step comprises reverse coating a second

layer of said hot melt composition on the said first mentioned layer to fill any depressions therein.

21. The method of producing a high gloss wax finish on flat paper box blanks, said method comprising the steps of successively applying a hot melt wax coating composition on one face of said blanks, then successively subjecting said coated face to chilling well below the melting point of said composition while simultaneously reverse roll coating said hot melt wax coating composition on the opposite face said blanks and then immediately and successively chilling the coating on said other blank face to well below said melting point.

22. A method as specified in claim 21 which includes the step of levelling said coating just before it is reverse roll deposited on said blanks.

23. A machine for producing high gloss wax finish on flat paper box blanks, said machine comprising roll coating means for depositing a layer of hot melt wax coating composition on one face of said blanks while advancing said blanks individually and successively along a path; reverse roll coating means further along said path depositing a layer of said composition on the other face of said blanks, means engaging said one coated face and frictionally advancing the same past said reverse roll coating means while simultaneously chilling said blank to well below the melting point of said coating composition and means engaging said other coated face and frictionally advancing the same further along said path while chilling said blank to well below the melting point of said composition.

24. A machine for producing a glossy coating on paper box blanks, said machine comprising means for feeding said blanks individually and successively along a path into a coating zone; coating apparatus in said coating zone, said apparatus comprising at least three pairs of opposed upper and lower rolls each having a nip along said path, means associated with the first pair of rolls for coating a layer of hot melt coating composition on one face of each successive blank while advancing said blank along said path; means associated with the second pair of rolls for reverse roll coating a layer of hot melt coating composition on the other face of each successive blank while simultaneously chilling and frictionally engaging the coating on said one face for advancing said blanks along said path, flexible blade means associated with said second pair of rolls for smoothing said layer just prior to coating the same on said blanks; means associated with said third pair of rolls for chilling and frictionally engaging the coating on said other face for advancing said blanks further along said path into a tempering zone, tempering means in said tempering zone, including an endless conveyor advancing said blanks through said zone into a quenching zone and a hot air oven coextensive in length with said zone, for heating the exposed area of the coating on said other face nearly to the melting point of said composition and quenching means in said quenching zone for rapidly cooling the said exposed area of said coating for hardening the glossy finish thereon.

25. A machine for producing a high gloss, hardened wax type finish on flat paper box blanks, said machine comprising roll means for applying a coating of hot melt wax composition to the lower face of said blanks while frictionally engaging the upper face thereof to advance the same along a path, a hot, reversely rotating, rubber roll mounted further along said path for applying a coating of hot melt wax composition to the upper face of said blanks; a chilled forwardly rotating steel roll, mounted opposite said rubber roll in pressure nip relationship therewith for engaging the coated underside of said blanks and advancing the same further along said path; a thin, flexible metal blade extending parallel to said rubber roll with its terminal edge portion tangential thereto for smoothing the coating on said roll; chilled forwardly rotating roll means mounted further along said path for

chilling and frictionally engaging said coated upper and lower faces to advance said blanks further along said path; a hot air oven mounted further along said path for softening the exposed area of the upper coated face of said blanks nearly to the melting point of said composition and waterfall quenching means mounted further along said path for quenching said exposed area into a hard finish.

26. A method for producing a high gloss finish on a plurality of flat paper box blanks advancing individually and successively along a path into the nip of a pair of opposed rolls, with a wet, slippery hot melt coating on one face thereof, one said roll having a hard smooth metal face and the other said roll having a yieldable rubber face, said method comprising the steps of simultaneously reverse roll coating a layer of said hot melt coating composition onto the other face of each successive blank from said rubber faced roll at said nip, thereby tending to urge said blanks rearwardly on said path, while chilling said hard, smooth faced roll at said nip and rotating same forwardly to harden the said wet, slippery hot melt coating on the said one face of each successive blank and advance the said blank through said nip.

27. Apparatus for producing a glossy coating on paper box blanks, said apparatus comprising a first pair of opposed, nip-forming rolls including a lower blank coating roll and an upper blank advancing roll; a second pair of opposed, nip-forming rolls including an upper blank coating roll and a lower blank advancing roll; a third pair of opposed nip-forming rolls including an upper blank glossing roll and a lower blank advancing and chilling roll; drive means for reversely rotating said glossing roll, forwardly rotating said lower blank advancing and chilling roll and rotating the other said rolls; means for supplying hot melt coating composition to the faces of said coating rolls, and means for chilling the face of said lower blank advancing and chilling roll whereby said blanks are advanced individually and successively through the nips of said first and second pairs of rolls and advanced through the nip of said third pair of rolls, despite said reversely rotating glossing roll, by said forwardly rotating chilling roll.

28. Apparatus for coating a plurality of box blanks in one pass through the coating zone of a coating machine, said apparatus comprising means for feeding said blanks individually and successively into said coating zone; a first pair of opposed rolls in said zone, said rolls having a nip for receiving and advancing said blanks along said zone; means on said machine for applying a coating to at least one roll of said first pair for coating at least one face of said advancing blanks; a second pair of opposed rolls in said zone, said rolls having a nip for receiving said blanks from the nip of said first pair of rolls; means for reversely rotating one roll of said second pair and forwardly rotating the other roll of said second pair, means for chilling the forwardly rotating roll of said second pair to grip and further advance said blanks through said nip and further along said zone; a coating face of rubber-like material on the reversely rotating roll of said second pair and means for applying a coating on the said face of said reversely rotating roll of said second pair for completing the coating of said advancing blanks.

29. Apparatus as specified in claim 28 plus means for heating the said rubber-like blank engaging face of said reversely rotating coating roll to a temperature substantially above the melting point of said coating.

30. Apparatus for coating a plurality of box blanks in one pass through the coating zone of a coating machine, said apparatus comprising means for feeding said blanks individually and successively into said coating zone; said means comprising at least one pair of opposed rolls and means for heating said rolls to pre-heat said blanks prior to arrival in said coating zone; a first pair of opposed rolls in said zone, said rolls having a nip for receiving and advancing said blanks along said zone; means on said

machine for applying a coating to at least one roll of said first pair for coating at least one face of said advancing blanks; a second pair of opposed rolls in said zone, said rolls having a nip for receiving said blanks from the nip of said first pair of rolls; means for reversely rotating one roll of said second pair and forwardly rotating the other roll of said second pair to grip and further advance said blanks through said nip and further along said zone; means for applying a coating on the said face of said reversely rotating roll of said second pair for completing the coating of said advancing blanks.

31. Apparatus for coating a plurality of box blanks in one pass through the coating zone of a coating machine, said apparatus comprising means for feeding said blanks individually and successively into said coating zone; a first pair of opposed rolls in said zone, said rolls having a nip for receiving and advancing said blanks along said zone; means on said machine for applying a coating to at least one roll of said first pair for coating at least one face of said advancing blanks; a second pair of opposed rolls in said zone, said rolls having a nip for receiving said blanks from the nip of said first pair of rolls; means for reversely rotating one roll of said second pair and forwardly rotating the other roll of said second pair; means for chilling the forwardly rotating roll of said second pair to grip and further advance said blanks through said nip and further along said zone; means for applying a coating on the said face of said reversely rotating roll of said second pair for completing the coating of said advancing blanks, and a thin flexible, resilient, continuous, wiping blade, mounted between said coating application means of said reversely rotating coating roll and the nip of said second pair of rolls for levelling the coating thereon in advance of the nip of said rolls.

32. Apparatus for coating a plurality of box blanks in one pass through the coating zone of a coating machine, said apparatus comprising means for feeding said blanks individually and successively into said coating zone; a first pair of opposed rolls in said zone, said rolls having a nip for receiving and advancing said blanks along said zone; means on said machine for applying a coating to at least one roll of said first pair for coating at least one face of said advancing blanks; a second pair of opposed rolls in said zone, said rolls having a nip for receiving said blanks from the nip of said first pair of rolls; means for reversely rotating one roll of said second pair and forwardly rotating the other roll of said second pair; means for chilling the forwardly rotating roll of said second pair to grip and further advance said blanks through said nip and further along said zone; means for applying a coating on the said face of said reversely rotating roll of said second pair for completing the coating of said advancing blank; a thin, flexible, resilient, wiping blade of heat absorbing material mounted between said coating application means of said reversely rotating coating roll and the nip of said second pair of rolls for levelling the coating thereon in advance of the nip of said rolls and blade mounting means of heat insulating material supporting said blade whereby the heat of hot coatings is absorbed by said blade but not dissipated by said mounting.

33. A machine for producing high gloss wax finish on flat paper box blanks, said machine comprising:
 roll coating means depositing a layer of hot melt wax coating composition on both faces of said blanks while advancing said blanks individually and successively along a path;
 roll glossing means comprising a smooth, blank-glossing roll and a smooth blank-advancing roll forming a nip further along said path;
 drive means for rotating said blank-advancing roll forwardly in the direction of advance of said blanks and for rotating said glossing roll reversely relative to the path of said blanks;
 means for maintaining said blank-glossing roll at least

at the melting point of said composition to burnish the coating engaged thereby; and means for maintaining said forwardly rotating blank-advancing roll at a temperature well below the melting point of said composition to harden and grip the coating engaged thereby for advancing the same through said nip against the reversing effect of said glossing roll.

34. A machine as specified in claim 33 wherein said roll-glossing means includes a scraper blade for removing accumulations from at least one of the rolls of said means.

35. A machine as specified in claim 34 plus endless conveyor means, in rear of said roll-glossing means, advancing said glossed blanks individually and successively further along said path; heating means, mounted along the path of said conveyor means, for softening, but not liquefying the glossed coatings on said blanks, and water fall type quenching means mounted further along said path for quickly cooling said softened coating to temper and harden said coatings without adversely affecting the gloss thereof.

36. A method for continuously producing a high gloss, smooth coating on flat box blanks, said method comprising the steps of advancing said blanks individually

5

and successively along a path while roll coating a thin layer of hot melt coating composition on one face thereof;

roll coating a thin layer of hot melt coating composition on the other face thereof; and then advancing said blanks individually and successively further along said path by chilled forward roll contact with the said coated one face thereof while reverse roll glossing the coating on the said other coated face thereof.
